UNITED STATES PATENT OFFICE.

ALFRED C. EGGERS, OF NEW YORK, N. Y., ASSIGNOR TO CHARLES A. TYRELL, OF NEW YORK, N. Y.

RECTAL SYRINGE.

1,087,935.

Specification of Letters Patent. Patented Feb. 24, 1914.

Application filed January 18, 1913. Serial No. 742,879.

To all whom it may concern:

Be it known that I, ALFRED C. EGGERS, a citizen of the United States of America, residing in New York, in the borough of Brooklyn, county of Kings, and State of New York, have invented certain new and useful Improvements in Rectal Syringes, of which the following is a specification.

This invention relates to that class of syringes which is used for irrigating the rectum and for flushing the colon, the syringe being intended to be used with a water-bottle by which the liquid for irrigation is supplied; and for this purpose the invention consists of a rectal syringe comprising a water-bottle, a conoidal head, a stem inserted into the upper end of the head, a coupling for connecting the base of the head with the water-bottle, a vertical channel in the upper part of said head, two horizontal channels separated by a horizontal partition in the head, said channels being connected respectively with the vertical channel and with the coupling of the water-bottle, and a loop-shaped tube connected with the horizontal channels and provided with a spring-clasp for conducting the liquid under pressure from the water-bottle through the tube and channels of the head to the stem of the same.

In the accompanying drawing, Figure 1 represents a plan-view of my improved rectal syringe, Fig. 2 is a side-elevation of the same, and Fig. 3 is a detail vertical transverse section through the head of the syringe, drawn on a larger scale.

Similar letters of reference indicate corresponding parts throughout the different figures of the drawing.

Referring to the drawings, *b* represents a water-bottle of any approved construction, which is provided at its center-portion with a coupling for applying my improved rectal syringe thereto. The coupling is formed of a threaded nipple *c* which extends from a center-plate *b*¹ of the bottle *b* into an interiorly-threaded recess *c*¹ in the base of the head *a*, so that a tightly-fitting connection between the water-bottle and the head is made. The head *a* is preferably made of conoidal shape and provided at its upper part with a detachable stem *d*, which is screwed into the upper end of the head.

The head *a* is preferably made of soft rubber or other suitable material and provided with a central channel *a*¹ in its upper portion, in line with the stem *d*, and with two horizontal channels *a*² in the body of the head *a*, said horizontal channels being separated by a partition *a*³, as shown clearly in Fig. 3. The upper channel *a*² is connected with the central channel *a*¹ and the lower channel *a*² with the coupling *c*. The ends of the channels *a*² are provided with screw-nipples *e*¹ to which is applied a loop-shaped liquid-conducting tube *e*, which can be opened or closed by means of a spring-clasp *e*² of the usual well-known construction.

When the rectal syringe is to be used, the water-bottle is filled with the liquid required and the stem of the syringe introduced into the rectum. The pressure exerted on the head of the syringe forces the liquid in the water-bottle through the coupling in the lower part of the head, the lower channel *a*², the loop-shaped tube *e* into the upper channel *a*² and then through the central channel *a*¹ and the stem *d* into the rectum, so as to produce the effective irrigation of the same and permit the supply of a considerable quantity of liquid through the rectum, which supply is regulated by the more or less continued pressure exerted by the body on the water-bottle.

When the rectal syringe is not desired to be used, it is unscrewed from the water-bottle and the coupling of the same is closed by a screw-cap, so that it can be used as an ordinary water-bottle. The screw-cap is removed when the water-bottle is to be used in connection with the rectal syringe, which is then replaced in position thereon and used as described.

The advantages of my improved rectal syringe are, first, that owing to the head being made of soft rubber, it dispenses with the expensive hard-rubber heads and valves for the same; second, that the direct pressure exerted on the head of the rectal syringe and on the water-bottle supplies the quantity of liquid required for irrigation without suspending the water-bottle at a higher level as heretofore; and, third, that the use of soft rubber for the head reduces the cost of the syringe to a considerable extent, so as to place it within the reach of a

greater number of persons than the expensive hard-rubber rectal syringes heretofore employed.

I claim:

- 5 1. A rectal syringe, comprising a water-bottle, a conoidal body thereon, a stem on the conoidal body, said conoidal body having a channel communicating with the interior of the water-bottle and a channel communicating with the stem, and a loop-shaped tube connecting the water-bottle channel with the stem-channel.
- 10 2. In combination, a water-bottle, a projecting body thereon, a channel in the same

communicating with the water-bottle, a 15 stem on the body, a channel in the body communicating with the stem, said channels normally not communicating with each other, and a loop-shaped tube connecting the channels for bringing about a communication thereof. 20

In testimony, that I claim the foregoing as my invention, I have signed my name in presence of two subscribing witnesses.

ALFRED C. EGGERS.
